UNITED STATES PATENT OFFICE.

EDWARD WELLINGTON, OF PORT COQUITLAM, BRITISH COLUMBIA, CANADA.

HAIR-BRUSH.

1,381,147.

Specification of Letters Patent. Patented June 14, 1921.

Application filed August 9, 1920. Serial No. 402,480.

To all whom it may concern:

Be it known that I, EDWARD WELLINGTON, a citizen of the Dominion of Canada, residing at Port Coquitlam, in the county of 5 Westminster and Province of British Columbia, have invented certain new and useful Improvements in Hair-Brushes, of which the following is a specification.

This invention relates to improvements in 10 hair brushes particularly adapted for use by ladies in brushing their hair.

At the present time, ladies when performing their toilet, require to brush their hair first on the outside surface and then follow 15 with a secondary operation of brushing the hair from underneath, and the present invention permits of these two operations being completed simultaneously, so that a considerable time is saved besides which a better brushing of the hair is accomplished.

In order that my invention may be properly understood, I have illustrated some preferred embodiments which will now be described in the specification, after which 25 the novel features will be disclosed in the claims.

In the drawings, there is shown a perspective view of my improved brush.

Referring to the drawings, 1 indicates my 30 improved hair brush comprising a pair of levers 2 of ogee shape connected intermediate of their length by a rivet or pivot pin 3, and the shorter arms of the levers are split and bent in opposite directions as shown at 35 4 and secured by screws or other suitable means to the backs of the brushes 5.

By reference to the drawings, it will be seen that the brushes are spaced apart with the bristles adjacent to each other.

40 Since the brushes are arranged transversely of the levers, they provide a long bearing surface, so that consequently a broad strand of hair can be brushed during each operation of the brush.

The longer arms 6 of the levers form the 45 hand grips and each hand grip is formed with a spring like member 7 which converge toward each other, so that the hand grips are normally held apart by the resilient force of the members 7.

The inner ends of the members 7 which abut or are located adjacent to each other, may for convenience be arcuate allowing 50 them to yield, as otherwise if the adjacent ends were flat they would act as a stop instead of a spring, but by the construction shown the brushes will be held in close contact with the hair so that when the brush is pulled by the user the desired friction is given to the hair.

55 It will be quite evident that a strand of hair placed between the brushes 5 will be simultaneously brushed on the outer and under sides.

I claim:

1. A hair brush comprising a pair of ogee levers pivoted intermediate their ends, the shorter arms of the levers each having two prongs lying in a single plane in the general direction of the levers, brushes connected to said prongs, and spring members carried by the longer arms of the levers and converging toward each other.

70 2. A hair brush comprising a pair of levers pivoted intermediate of their ends, 75 brushes attached to one end of the levers and transversely thereof with the bristles disposed toward each other, said levers being shaped so that their ends are opposed spring members on the other end of the levers, the 80 spring members converging and having their ends adjacent.

In testimony whereof I affix my signature in the presence of two witnesses.

EDWARD WELLINGTON.
